(57) **CLAIM**

The ornamental design for a split-loop offset catheter securement device, substantially as shown and described.

DESCRIPTION

FIG. 1 is a top plan view of a catheter securement device with an offset split loop retention member;

FIG. 2 is a top isometric view of the catheter securement device according to FIG. 1 with both of the split loop retention members lifted in an open position;

FIG. 3 is a bottom elevation view of the catheter securement device according to FIG. 1;

FIG. 4 is a right side view of the catheter securement device according to FIG. 1;

FIG. 5 is a left side view of the catheter securement device according to FIG. 1;

FIG. 6 is a front side view of the catheter securement device according to FIG. 1;

FIG. 7 is a back side view of the catheter securement device according to FIG. 1;

FIG. 8 is a top plan view of a catheter securement device according to FIG. 1 where a catheter hub is secured beneath a first of the two retention members;

FIG. 9 is a top plan view of the catheter securement device according to FIG. 8 where a first lumen is secured beneath a second of the two retention members and a second lumen is located above the second of the two retention members; FIG. 10 is a perspective view of the catheter securement device according to FIG. 9 where the lumens are being pulled upwardly to show that the forces of the first lumen are being accepted by a different one of the two retention members than the forces of the second lumen;

FIG. 11 is a right side view of the catheter securement device according to FIG. 10 where the lumens are being pulled upwardly to show that the forces of the first lumen are being accepted by a different one of the two retention members than the forces of the second lumen; and,

FIG. 12 is a top plan view of the catheter securement device according to FIG. 9 where the lumens are being pulled axially.

(Continued)

The broken lines in the figures illustrate environmental structures and portions of the design that form no part of the claimed design.
